[57] CLAIM

The ornamental design for a digital multimeter or the like, substantially as shown and described.

DESCRIPTION

FIG. 1 is a top elevational view of a digital multimeter showing my new design;

FIG. 2 is a side elevational view thereof;

FIG. 3 is a bottom elevational view thereof;

FIG. 4 is a front elevational view thereof;

FIG. 5 is a rear elevational view thereof;

FIG. 6 is a partial perspective view of the upper area of a digital multimeter showing another embodiment of my new design of FIG. 1 wherein a differently shaped contact point has been substituted for that of FIG. 1, all other portions being identical.

FIG.1

FIG.2

FIG.3

FIG.4

FIG.5
